Atty.

UNITED STATES PATENT OFFICE.

CYRUS BAILEY, OF CHICAGO, ILLINOIS.

CARPENTER'S PLANE.

1,418,513.

Specification of Letters Patent. Patented June 6, 1922.

Application filed July 10, 1920. Serial No. 395,300.

To all whom it may concern:

Be it known that I, CYRUS BAILEY, a citizen of the United States of America, and a resident of Chicago, Illinois, (where he is now living and receives mail), have invented a certain new and useful Improvement in Carpenters' Planes, of which the following is a specification.

This invention contemplates certain improvements on the plane shown and described and covered broadly in Patent No. 1,348,923.

Objects of the improved construction are to provide means to facilitate the adjustment of the bit or blade to insure an accurate cutting action; to provide means for locking the tilting handle against movement, so that the plane can be used like the ordinary tool in which the bit or blade is not movable; and to provide certain details and features of construction and combinations tending to increase the general efficiency and the desirability of a carpenter's plane of this particular character.

To these and other useful ends the invention consists in matters hereinafter set forth and claimed and shown in the accompanying drawings, in which—

Fig. 1 is a longitudinal section of a carpenter's plane embodying the principles of the invention.

Fig. 2 is a vertical section on line 2—2 in Fig. 1.

Fig. 3 is a detail section on line 3—3 in Fig. 1.

Fig. 4 is a detail section on line 4—4 in Fig. 1.

As thus illustrated, the invention comprises a flat body 1 having sides 2 and a transverse slot 3 at the bottom thereof. The bit or blade holder 4 forming a bed for the bit end is pivoted at 5 between the sides 2 and has a rearwardly extending rigid portion 6 which is bifurcated at its rear end to embrace the base portion 7 of the handle 8, which handle is fulcrumed at 9 on the body and held in place thereon by an adjustable screw 10 inserted downwardly. The rear extension 6 of the blade or bit holder is pivoted at 11 on the base portion 7 of the handle, whereby the tilting movement of the latter, when the plane is shoved forward and drawn back in the ordinary manner, causes the blade or bit holder 4 to tilt about its pivot 5, in a manner that will be readily understood. This tilting action, however, can

be prevented by rotation of the thumb wheel 12 which is inserted through the rear portion of the handle base 7, and which is provided with a screw 13 for engaging the flat spring 14, which latter is rigidly secured to the body 1 by means of a screw 15, in the manner shown. When the spring 14 is pressed downward by rotation of the screw 12, and by the pressure of the screw 13, it thereby holds the handle 8 against any tilting motion about its fulcrum on the body 1, so that the edge of the bit is held in cutting position. The screw device 16 is applied to the rear extension 6 of the blade or bit holder 4 to regulate the tilting action of the latter. The blade or bit 17 is secured to the cap plate 18 by a screw 19, the head of which latter is adapted to be received in the round opening 20 formed in the upper extension of the blade or bit holder 4, so that the cap plate 18 is non-adjustable up and down on the holder or bed for the plane and the screw 19 thus forms a pivot about which the blade and its cutting edge can be oscillated in the slot 3, during adjustment of the blade, thereby to accurately position the edge of the blade relatively to the flat lower surface of the body 1 of the plane. During this adjustment the user can place a thumb on the lower portion of the plate 18, while holding the plane upside down, thereby to keep the blade in position, and when the desired adjustment is found, the clamp 21 is then applied to tightly clamp the blade or bit 17 and its plate 18 in position on the blade or bit holder 4 previously described. The said clamp 21 has its lower portion formed with a notch 22 which not only receives the screw 23, the latter being inserted in the blade or bit holder, but which also affords access to the lower portion of the plate 18, so that the latter can be held in place by the thumb in the manner previously explained. In other words, the thumb is retained on the cap plate 18, and can remain in position, because of the notch 22, until after the cam 24 of the clamp is actuated to press the spring 25 against the plate 18, thus using the screw 23 as a fulcrum by which to cause the upper and lower ends of the clamp to bear upon the plate 18 with sufficient pressure to hold the blade or bit in place. As stated, accurate adjustment of the blade requires that it be held in place by the pressure of the thumb on the lower portion of the plate 18, and this pressure can be continued until after the

clamp 21 is firmly secured in place, by reason of the notch 22, the thumb being received in this notch when the clamp is caused to slide endwise into position, and as soon as the clamp is thus in position, and while the thumb is still in the notch 22 and firmly holding the bit or blade in place, the other hand is then used to manipulate the cam 24 to clamp the bit or blade in place on the 10 blade or bit holder 4, after the adjustment of the cutting edge of the blade has been accurately determined, relatively to the flat bottom surface of the plane. Of course, as in any plane, the lower edges of the bit 17 15 and the cap plate 18 must be accurately set or adjusted relatively to each other and this adjustment must be preserved by tightening the screw 19, whereby the bit holding means thus provided must be used with a tilting bed to give the adjustment necessary for 20 properly positioning the edge of the blade on the bottom of the plane.

Thus a tilting blade or bit holder is provided which automatically raises and lowers the cutting edge of the blade when the plane is moved back and forth, so that the edge of the blade will not drag on the lumber when the plane is moved or pulled backward. In addition, the blade or bit holder 25 is provided with means to facilitate the accurate adjustment of the blade or bit, and the clamping of the same in position thereon. Again, as explained, means are provided for locking the blade or bit holder 30 against tilting movement, and while a thumb wheel 12 is preferably employed for this purpose, in the manner shown and described, it will be understood that any suitable means can be employed to accomplish 35 the desired result, whereby the plane can be used without the automatic tilting of the blade or bit, and with the latter practically rigid with the body 1, if such is necessary or desirable.

With further reference to the adjustment of the blade or bit, it will be observed that the said blade or bit has a longitudinal slot 26 for the screws 19 and 23, and thereby accurate adjustment of the cutting edge of the 40 blade relatively to the lower edge of the plate 18 may be obtained before the screw 19 is tightened to clamp the blade and the plate together. It will be understood, of course, that this relative adjustment between the blade and the plate, and the 45 tightening of the screw 19 to clamp them together, is all accomplished before the blade or bit and its plate are inserted in the plane, so that in this way the distance of the cutting edge below the flat bottom surface of the plane is determined before the blade is inserted in the plane. When this adjustment 50 of the blade is finally accomplished, it is then necessary to true the edge of the blade relatively to the bottom surface of the plane,

so that the cutting edge will be exactly horizontal, or as nearly parallel as possible with the lower surface of the plane, and this is done by tilting or oscillating the blade and its plate about the inclined axis provided by 55 the screw 19, as previously explained. The plate 18 also has an opening 27 for the screw 23, this opening being of sufficient size to provide ample clearance all around its edge for said screw, so as not to interfere with the insertion or removal of the 60 blade or the adjustment thereof.

The handle 8 can be secured to its base 7 in any suitable or desired manner. For example, a long screw 28 can be inserted 65 downwardly through the handle into the base 7 to clamp the handle tight upon said base. Preferably the handle is made of wood and the base of metal. A front handle 29 can be provided and secured in any suitable manner to the front portion of the body.

As the screw head 19 fits the hole 20 in the holder, it follows that the blade or bit, (while in the plane) is not adjustable up and down or slidable on the holder, or on the bed as it is called in an ordinary plane, whereby the tilting of the holder is necessary with bit or blade holding means of this kind, for without such tilting adjustment the extent to which the cutting edge of the blade projects below the bottom of the plane could not be changed (while the blade is in position in the plane, as is necessary) to regulate the cutting action.

What I claim as my invention is:—

1. In means for supporting and positioning the blade or bit of a plane, a blade or bit holder, a blade and a cap plate secured together by a screw, the said holder having an opening to receive the head of said screw, so that the cap plate is non-adjustable up and down on said holder which forms a bed for the bit, whereby the blade or bit although held or anchored against up and down adjustment can be oscillated to accurately adjust the cutting edge thereof, relatively to the bottom surface of the plane, a clamp for engaging said plate to clamp the blade or bit in position, said clamp having a notch at its lower end to permit pressure on the lower portion of said plate to hold the blade or bit in place while the clamp is being adjusted into position, means for entering said notch and securing the clamp in place, and means to support and adjust said holder in position to accurately present the edge of the blade.

2. A structure as specified in claim 1, said blade or bit holder having a screw which is received in said notch when the clamp is caused to slide downward endwise into position.

3. In means for supporting and positioning the blade or bit of a carpenter's plane,

- the combination of a body, a blade or bit and a holder therefor pivoted on the body, a handle fulcrumed on the body and connected to oscillate said holder to automatically raise and lower the edge of the blade or bit when the plane is moved forward and backward, so that the edge of the blade is automatically raised when the plane is pulled backward, and a device carried on said handle and adjustable about a transverse axis into position in the bottom portion of the handle to prevent said tilting motion of the holder when it is desired to use the plane without said automatic raising and lowering of the blade or bit.
4. A structure as specified in claim 3, said device comprising a rotatable element, a spring and means on said element to engage said spring, thereby to prevent tilting motion of the handle.
5. A structure as specified in claim 3, said handle having a hollow base portion, and said device being enclosed in said base, a portion of said device being exposed for manual manipulation thereof.
6. A structure as specified in claim 3, said device being applied in rear of the fulcrum of said handle.
7. A plane comprising a body, a blade holder pivoted on said body and provided with a rearwardly extending rigid bottom portion overlying the body in rear of said pivot, a blade adjustably mounted but anchored against up and down sliding movement on said holder in front of said pivot, so that the cutting edge of the blade may be raised and lowered only by up and down tilting motion of said rigid bottom portion of the holder, a clamp having its lower end provided with a notch, means to enter said notch to hold the clamp in position to clamp the blade in position, said notch permitting pressure on the blade during the adjustment thereof, and also while the clamp is being moved endwise into position, and means to regulate the tilting motion of said holder to ensure accurate presentation of the cutting edge of the blade, after the blade is secured on said holder.
8. A plane comprising a body, a blade holder pivoted on said body and provided with a rearwardly extending rigid bottom portion overlying the body in rear of said pivot, a blade adjustably mounted on said holder in front of said pivot, so that the cutting edge of the blade will be raised and lowered by up and down tilting motion of said rigid bottom portion of the holder, and a handle having a fulcrum on the body and adapted for operating the plane and connected at its lower end to said rearwardly extending portion for tilting said holder about its pivot to raise the blade when the plane is pulled backward and to lower the blade when the plane is pushed forward, the handle thereby having rearward and downward movement to lift the blade, and forward and upward movement to lower the blade, in combination with a device engaging the bottom portion of the handle in rear of said fulcrum to lock the handle in raised position against backward movement when it is desired to use the plane without said raising and lowering movement of the blade.

CYRUS BAILEY.
